UNITED STATES PATENT OFFICE.

WILLIAM A. LORENZ, OF HARTFORD, CONNECTICUT, ASSIGNOR TO UNION PAPER BAG MACHINE COMPANY, OF PHILADELPHIA, PENNSYLVANIA, A CORPORATION OF PENNSYLVANIA.

ART OF MANUFACTURING SQUARE-BOTTOM PAPER BAGS.

SPECIFICATION forming part of Letters Patent No. 689,499, dated December 24, 1901.

Application filed March 19, 1901. Serial No. 51,818. (No model.)

To all whom it may concern:

Be it known that I, WILLIAM A. LORENZ, a citizen of the United States, residing at Hartford, in the county of Hartford and State 5 of Connecticut, have invented certain new and useful Improvements in the Art of Manufacturing Square-Bottom Paper Bags, of which the following is a full, clear, and exact specification.

- 10 This invention relates to the art of manufacturing square-bottom paper bags; and it has for its object an improved method of forming the so-called "diamond fold" in a bellows-sided or tucked tube or blank, such 15 method being adapted for use in connection with any well-known method of previously forming the tube or blank and of subsequently pasting and folding the diamond to complete the bag.
- 20 My invention has more particularly for its object an improved method of opening out the open or bottom-forming end of the blank, so as to form the inside triangular folds in an easy and rapid manner.
- 25 My improved method includes as one of its features the engagement separately of the upper and lower plies of the tube and then folding the same in opposite directions over and around adjacent folding edges, the dis- 30 tance from each of said points of engagement to the folding edges being primarily less than the depth of the tucks. Furthermore, after said plies have been folded back, so that the engagement-points have arrived in 35 positions at opposite sides of the adjacent folding lines or edges and substantially at right angles with the body of the blank at said lines, the distance between said points of engagement is increased until the tucked 40 sides have been completely stretched out be- tween them, so that finally the distance from said points to the folding-lines will be sub- stantially equal to the depth of the tucks.

One of the ordinary methods of forming the diamond on a bag-blank comprises the engagement of the upper and lower plies thereof by suitable devices generally known as "tuck" and "box" holders at such points,

the distance of which from the bottom-defining line is substantially equal to the depth 50 of the tucks, so that as said points are separated said tucked sides will be gradually stretched out to develop the inside triangular folds. The method of straightening out the tucked sides is usually carried out by swinging the devices which engage one ply of the blank away from those engaging the other 55 ply and substantially around the defining-line as an axis, the distance from each of said devices to the defining-line remaining uniform 60 throughout the folding operation. In my improved method, however, the plies of the blank are manipulated in such a manner that the sides will have been distended but partially between the points of engagement even 65 after the latter have arrived at positions at opposite sides of the folding-line, so that subsequently the distance between such points must be increased in order fully to stretch the tucked sides of the tube. 70

Furthermore, my improved method comprises as one of its features the manipulation of the blank in the above manner, while the upper and lower plies are preferably maintained in close proximity to each other 75 during the period when the distance between the box-holders and tuck-holders is increased to distend or stretch the tucked sides to the required extent. Furthermore, I have found in practice that when the line of travel or 80 movement of the box and tuck holders is substantially at right angles with the body of the blank while the tube plies are kept close together the inside triangular folds may be developed gradually and in an easy manner, 85 said folds maturing in the nature of a running fold during the distension of the tucked sides.

My improved method is clearly illustrated in the accompanying drawings, in which similar characters denote similar parts, and in which--

Figure 1 is a side view of a blank, illustrating the manner in which the blank plies are engaged by the several instrumentalities employed during the diamond-forming opera- 95

tion. Fig. 2 is a top view of Fig. 1, and Fig. 3 is an end view of the blank. Fig. 4 illustrates the blank opened out to a small extent. Fig. 5 is a front view thereof. Figs. 6 and 7 show a condition of the bag when the distance between the folding instrumentalities has been increased, but the sides have not been fully distended; and Figs. 8 and 9 show a side view and front view, respectively, of the blank 10 when the distance between the box-holders and tuck-holders is substantially equal to the depth of the tucked side, so that the latter is completely stretched out and the inside triangular folds have been fully developed.

15 In the drawings the blank 10 is shown as having tucked or bellows sides 11 and comprising the bag-section A and the bottom-forming section A', the boundary-line between said sections being generally known as the 20 "defining-line" and indicated in the present instance by d .

Referring to Figs. 1 and 2, it will be seen that the upper ply of the blank is engaged by the so-called "box-holders" B, which, in conjunction with grippers b, serve to fold the upper ply 12 around the edge f of a member F, which constitutes the folding member for the upper ply of the blank, while a similar member F', having an edge f' , forms the folding 30 member for the lower ply 13 of the tube. The lower ply is herein shown engaged by tuck-holders T, which coöperate with pincers t and whereby said lower ply 13 is folded around the edge f' , the positions of the box-holders 35 and tuck-holders B and T after performing their proper function in folding the respective plies around the folding edges f and f' being clearly shown in Fig. 4.

Again referring to Fig. 1, it will be seen that 40 the points of engagement 15 are disposed at a distance from the defining-line d equal to the depth of the tucks and that, furthermore, the folding edges f and f' are disposed between the points 15 and said defining-line d , 45 the position of the folding-line relative to the defining-line remaining substantially the same as the plies of the tube are bent outward from the position shown in Fig. 1 to that shown in Fig. 4, in which the plies of the tube 50 are shown substantially at right angles with the body of the tube at the folding-lines. In the further manipulation of the blank the box-holders and tuck-holders are moved in the direction of the arrows 16 and 17, respectively, 55 thereby drawing the plies over their respective folding edges f and f' , and thus gradually forming the inside triangular folds after passing the intermediate position shown in Figs. 6 and 7 to that shown in Figs. 8 and 9, when 60 the tucked tube sides have been fully distended or stretched to complete the box, which may then be transformed into the diamond. (Shown in dot-and-dash lines in Figs. 8 and 9.)

65 In the present case I have shown the fold-

ing members F and F' as being stationary, so that when the box and tuck holders are moved away from each other the tube will be drawn forward between said members; but it will of course be understood that said members F and F' may have a movement toward the left while the bag-blank remains stationary, such movement being proportionate to the movement of the box-holders and tuck-holders away from each other.

70 From the foregoing it will be seen that the movement of the box-holders and tuck-holders will produce a running fold in each of the tube plies over the edges f and f' , while the bag-blank is maintained in substantially 75 closed position.

Having described my invention, what I claim as new, and desire to secure by Letters Patent, is—

1. The improvement in the art of forming a diamond in square-bottom paper bags which comprises folding over the tube plies in opposite directions and between such points thereof, the distance of which from the primary folding-line is less than the depth of the 90 tucks.

2. The improvement in the art of forming a diamond in square-bottom paper bags which comprises folding over the tube plies in opposite directions and between such points 95 thereof, the distance of which from the primary folding-line is less than the depth of the tucks, and increasing the distance between said points until the tube sides are completely distended between them.

3. The improvement in the art of forming a diamond of square-bottom paper bags which consists in the engagement of the sides of the upper and lower tube plies at points, the distance of which from the primary folding-line 105 is less than the depth of the tucks; folding over both plies in opposite directions to positions, substantially to form right angles with the tube-body at the folding-line, and subsequently increasing the distance between 110 said points to develop the inside triangular folds.

4. The improvement in the art of forming the diamond of square-bottom paper bags which comprises the engagement of the sides 115 of the upper and lower tube plies at such points thereof, the distance of which from the primary folding-line is less than the depth of the tucks, maintaining the tube plies in closed condition, folding over both plies in opposite 120 directions to positions substantially at right angles with the tube-body at the folding-line, increasing the distance between the points of engagement to develop the inside triangular folds, and subsequently completing the diamond. 125

5. The improvement in the art of forming the diamond of square-bottom paper bags which consists in engaging the plies at such points thereof, the distance of which from the 130

defining-line is equal to the depth of the tucks, folding over said plies in opposite directions at and around corresponding primary folding-lines located between the points of engagement and the defining-line, and subsequently increasing the distance between said points of engagement until the tucked sides are fully

distended between them and until the defining-line and the folding-line substantially coincide.
